WITNESS:

Arthur J. Shaukis,
INVENTOR
BY *Victor J. Evans*

ATTORNEY

UNITED STATES PATENT OFFICE

ARTHUR J. SHAUKIS, OF HAVERHILL, MASSACHUSETTS

ATOMIZER

Application filed October 19, 1928. Serial No. 313,518.

This invention relates to atomizers, and its general object is to provide an improved atomizer that is primarily designed for use with perfumes, toilet waters and the like, 5 is non-leaking and air-tight when closed, and includes improved automatic and manually controlled air and liquid valves, which together with other improved features make up an atomizer that is simple in construction, reasonably inexpensive to manufacture and above all is extremely efficient in operation and service.

A further object of the invention is to provide an atomizer that is an improvement on 15 the disclosures that form the subject matter of my application Serial No. 99,648, that terminated in Patent No. 1,677,053, dated July 10, 1928, and my prior application Serial No. 149,682.

20 This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several 30 views, and in which:

Figure 1 is an elevation of my improved atomizer.

Figure 2 is a vertical longitudinal sectional view taken therethrough with parts in elevation. 35

Figure 3 is an enlarged sectional view taken through the head.

Figure 4 illustrates a modified form.

Figure 5 is a sectional view showing fragmentary portions of the container and air bulb and the connection between the same, with the air tube in elevation. 40

Figure 6 is a similar view illustrating the check valve.

45 Referring to the drawings in detail, the reference numeral 1 indicates the base of the atomizer which forms the subject matter of the present invention and the base is provided with a centrally disposed opening that receives the depending shank 2 of a collar

3 which is provided with a bore that extends into the shank 2, and the portion of the bore within the shank 2 opens to the atmosphere and is relatively smaller than the bore of the collar. Superposed with respect thereto 55 and resting upon the collar is a ring member 4 which has arranged thereon a ferrule 5, and the ferrule 5, the collar and ring have extending therethrough the lower end of an air tube 6 which terminates in the bore of 60 the collar 3 as clearly shown in Figure 6 of the drawings. The bottom of the air tube is formed with diametrically oppositely disposed recesses 7 to provide air passages when the ball 8 is arranged in contacting engagement 65 with the lower edge of the tube, the ball normally closing the small portion of the bore that is arranged at the shank 2.

Surrounding the tube and having its small 70 ends disposed in contacting engagement therewith is a bulb 9 formed from rubber or the like, and the lower end of the bulb 9 is received in the ferrule 5 while its upper end is received in a ferrule 10 which is connected with a ferrule 11 by a sleeve 12 that is disposed in contacting engagement with the tube as clearly shown in Figure 2. Surrounding the sleeve 12 is a ring member 13. The ferrule 11 is provided with an outwardly flared 75 upper portion for the purpose of accommodating the reduced lower end of a substantially oval shape container 14 which may be formed from glass that may be colored if desired, but in any event the container is provided with a relatively large neck 15 having screw threads 80 on its outer surface for the purpose of accommodating the threaded flange 16 of the head of the atomizer which I have illustrated in two forms, namely that shown in Figures 2 and 3 and that shown in Figure 4. 85

The forms of heads of my atomizer are somewhat similar, and the head as shown in Figures 2 and 3 includes a solid portion 17 that has its outer surfaces covered with sheet metal in the form of an inverted cup 18 which is formed integral with the threaded flange 16. The cover for the solid portion 17 has arranged in its upper end an opening to accommodate the threaded shank of a knob 19, 90 the threaded shank being received in a bore 95

20 vertically disposed in the solid portion and arranged in communication with an inclined bore 21 having a threaded outer end for the purpose of accommodating the threaded nipple of a nozzle 22.

5 The nozzle includes a relatively small pipe section 23 that is bent intermediate its ends for disposing portions thereof in the respective bores as well as in a relatively small

10 bore arranged in communication with the vertical bore 20. The pipe section 23 is of a size to snugly fit in the upper end of the air tube 6 which has disposed between the same and the solid portion 17 a gasket 24 that

15 surrounds the pipe section 23 as clearly shown in Figure 3.

The air tube 6 extends centrally through the bulb, sleeve 12 and container, and in order to provide an air-tight connection between the tube and the bottom of the container, I provide a collar 25 that is formed with a flange arranged in air-tight connection with the bottom of the container as shown in Figure 2.

25 Disposed at right angles to the vertical bore 20 is a threaded bore that threadedly receives the threaded stem 26 of a thumb screw 27, the stem 26 providing a valve for closing a vent opening 28 formed in the 30 solid portion 17 at its juncture with its covering.

Threadedly secured in the solid portion and depending therefrom in parallelism with the air tube is a liquid tube 29 that is also controlled by the threaded stem of the thumb screw 27. The liquid tube 29 terminates above the bottom of the container and is of course adapted for drawing the liquid therefrom as will be apparent, as the upper end of the liquid tube terminates for communication with the bore that is disposed at right angles to the vertical bore 20.

35 In the form of head as shown in Figure 4, it will be noted that all of the elements thereof are similar to the head as shown in Figures 2 and 3, with the exception that the valve for controlling the vent opening and liquid tube is not only provided with a threaded stem 30 but is also formed with a conical portion 31 which is provided with a like shape portion formed in the outer end of the bore that receives the threaded stem 30.

50 The portion of the air tube that is disposed within the bulb is provided with a plurality of openings 32 so that the air within the bulb will be introduced within the tube, and the air enters the bulb 9 through the valve controlled bore in the shank 2, as well as through the air tube, when the bulb is expanded, but 55 when the bulb is compressed the air within the same will be forced into the air tube, and thence into the pipe section 23 and nozzle 22. This action of the air will create a suction in the bores 20 and 21 which will draw the 60 liquid from the container through the liquid

tube 29, the valve controlled bore, bores 20 and 21, and thence the liquid will be sprayed through the nozzle 22.

65 A gasket 33 provides a leak proof connection between the head and the container, and due to the slip joint between the pipe section and air tube, it will be obvious that the head is readily removable from the container when the latter is unscrewed therefrom.

70 From the above description and disclosure of the drawings, it will be obvious that my improved atomizer is positively leak proof and is extremely efficient in operation and service.

75 It is thought from the foregoing description that the advantages and novel features of my invention will be readily apparent.

80 I desire it to be understood that I may make changes in the construction and in the combination and arrangement of the several parts, provided that such changes fall within the scope of the appended claims.

85 What I claim is:

1. An atomizer of the character described comprising a base, an air tube having openings therein, means supported by said base and carrying said air tube, a check valve carried by said means and adapted for controlling the air through said air tube, a bulb surrounding a portion of said air tube that is formed with openings, a container supported above said bulb and disposed about said air tube, a head for said container and being provided with a vertical bore communicating with an inclined bore and a horizontal bore, an air-tight connection between said head and air tube, a nozzle secured to said inclined bore, a pipe section between said nozzle and air tube, a liquid tube depending from said head and arranged in said container, said liquid tube being in communication with the horizontal bore, said head being formed with an air vent and means received in the horizontal bore and controlling the air vent and communication between the liquid tube and the nozzle.

90 100 105 110 115 120 125 130

2. An atomizer of the character described comprising a base, an air tube, means supported by said base and receiving the lower end of the air tube which is provided with diametrically oppositely disposed notches, a check valve carried by said means and controlling the lower end of said air tube, a bulb surrounding a portion of said air tube that is provided with openings, a container surrounding the air tube, means of connection between the bulb and container, a head for said container and being removably associated therewith, a solid portion formed in said head and being provided with a vertical bore communicating with an inclined bore, and a horizontal bore, a nozzle threadedly secured in the inclined bore, means of communication between the nozzle and air tube, a liquid tube secured to and depending from the solid

portion, said liquid tube being in communication with the horizontal bore and having its lower end terminating adjacent the lower end of the container, said solid portion being provided with a vent opening communicating with the container, and means threadedly received in the horizontal bore for controlling the vent opening and communication between the liquid tube and the nozzle.

3. An atomizer of the character described comprising a base, a collar including a shank disposed in said base and being provided with a bore having a restricted portion disposed in said shank for communication with the atmosphere, an air tube arranged in said collar and having a notched lower end, a ball loosely mounted in said shank and controlling the restricted portion of the bore and air to the air tube, a bulb supported above the collar and disposed about a portion of said air tube that is formed with openings, an oval shape container surrounding said air tube, ferrules receiving the adjacent ends of said container and bulb respectively, a sleeve connecting said ferrules and surrounding said air tube, a ferrule receiving the opposite end of said bulb, ring members between the first mentioned ferrules and the last mentioned ferrule and collar, a head detachably secured to said container and closing the upper end thereof in an air-tight manner, a solid portion included in said head, a nozzle carried by said head and being in communication with the air tube and container respectively, said head being provided with a vent opening disposed in communication with the container, a liquid tube depending from said head and arranged in said container, and means for controlling the vent opening and communication between the liquid tube and nozzle.

In testimony whereof I affix my signature.
ARTHUR J. SHAUKIS.
